UNITED STATES PATENT OFFICE.

OLAF L. HOWE, OF MISSOULA, MONTANA.

AIR-MOTOR.

1,275,030.

Specification of Letters Patent.

Patented Aug. 6, 1918.

Application filed May 17, 1915. Serial No. 28,779.

To all whom it may concern:

Be it known that I, OLAF L. HOWE, of Missoula, in the county of Missoula and State of Montana, have invented certain new 5 and useful Improvements in Air-Motors; and I do hereby declare the following to be a full, clear, and exact description of the invention, such as will enable others skilled in the art to which it appertains to make 10 and use the same.

The object of this invention is to provide an extremely simple and highly efficient air motor having means whereby the traveling vanes will be automatically kept in proper 15 direction relatively to the wind.

And a further object is to provide simple and highly efficient means for stopping the motor.

In the accompanying drawings, Figure 1 20 is a plan view. Fig. 2 is an elevation. Fig. 3 is a fragmentary view showing the means for stopping the motor. Fig. 4 is an enlarged fragmentary view of one of the vanes and its connections to the traveling cables. Fig. 5 is an enlarged fragmentary view of a 25 vane shutter. Figs. 6, 7 and 8 are details.

Referring to the drawings, 1 designates a rectangular frame which is composed of suitable upper and lower bars connected together by cross-rods, said frame being centrally supported by a vertically-disposed shaft 2, to which latter are connected horizontally-disposed tension rods 3 which extend from said shaft toward the ends of 30 the rectangular frame and form in part bearings for the journals 3^a of sheave wheels 4 at opposite ends of the frame. There are two of these sheave wheels at each end of the frame and with them engage upper and 35 lower endless cables 5.

6 designates a series of vertically disposed vanes mounted between and connected to the upper and lower bars 7 which are connected together by the pivot rods 8 of the several 40 shutters 9, one of which latter is shown in Fig. 4 and a fragmentary portion of another in Fig. 5. Each vane has a vertically disposed supporting rod or shaft 10, arranged about midway of its length in the same vertical plane with the said upper and lower cables, as shown in Fig. 4. These shafts extend through the upper and lower bars 7 and the vanes are connected by clips 12 to the cables 5, such clips being bent to accommodate the sheaves and also formed with bearings 13 to accommodate shafts 10, such shafts

being keyed by a bolt 14 to the clips 12. The vane frames are free to turn independently of the shaft when it is desired to change the position of the vanes relatively to the supporting cables. 15 designates a laterally extending arm secured at one end by a clip 15^a to the lower cable, the other end of said arm being secured to the pivot rod 8 of one of the shutters, which pivot rod is 60 elongated for that purpose, as shown in Fig. 4. Each of the arms 15 is provided with two upturned flanges 15^b between which are spring plates 16 bowed at their centers and forming spaces at their opposite ends to accommodate the pivot rod 8.

17 designates a circular track upon which travel rollers 18 supported by brackets 19 depending from frame 1. 20 is a vane or rudder which is pivotally mounted on one of the shafts 3^a and which extends diagonally beyond the rectangular frame 1 and carries a roller 21 which also travels on track 17. The vane or rudder is secured to the frame by means of a brace 22, as shown in Fig. 1, said brace extending diagonally from said frame, and having means permitting the rudder to be differently positioned relatively to the frame. By means of the rudder the series of shutter-carrying vanes are always kept in the wind, that is to say, they are so presented to the air current that in traveling in one direction the shutters of all of the vanes on one side of the frame will be closed, presenting an unbroken or solid 75 surface to the wind, while in traveling in the opposite direction they will be opened, offering the minimum of resistance to the air. Thus, as shown in Fig. 1, the shutters of the vanes on one side are practically all closed while those of the other side are opened, the opening occurring as the vanes make the turn at one end of the frame and the closing as they make the turn at the opposite end. The power is transmitted from the two end shafts 3^a to the central shaft 2 by means of two cables 23 and 24, as shown in Fig. 2. On shaft 2 below the track 17 is a pulley 25 by which power may be transmitted by a belt or cable.

In order to stop the operation of the machine, I employ an arm 26 carrying a roller 28 which may be projected into the path of the vanes by pulling on a cable 29. Ordinarily the roller is held out of the way by a spring 30. As each of the vanes engages with roller 28 it is turned on its pivot, as

shown in Fig. 3, and this causes the elongated pivot rod 8 to pass from the outer end of arm 15 to the inner end thereof, the spring-plates 16 holding the rod in the position to 5 which it is moved and the vane out of the wind. It is only necessary that those vanes whose shutters are closed to the wind be turned in line with the wind so that the air current will have no effect thereon, the shutters on the vanes on the opposite flight being opened. For throwing the vanes back into operative position I have shown a rod 31 vertically disposed in the framework between the two flights of the cable, such rod 10 being capable of being projected into the path of the inner sides of the vanes so that the latter will be turned upon engagement therewith.

To prevent undue strain on the cables by 20 the wind striking the closed shutters, I provide the vanes at their inner ends with rollers 33 which are mounted on the lower supporting bars 7, these rollers bearing against a centrally arranged horizontal rod 25 34 extending longitudinally of and supported by the frame, sufficient clearance being allowed at the ends to prevent interference with the turning of the vanes when desired.

30 The advantages of my invention will be readily appreciated by those skilled in the art. Although I have specially described it as an air motor, yet it will be understood that the same may be employed as a water motor. In practice, when the vane or rudder has thrown the frame into the wind the shutters of all the vanes on one side will be automatically closed by the wind pressure and as the several vanes successively 35 travel onto the opposite side of the frame their shutters will be automatically opened. The travel of the vanes effects the turning of the two ends shafts from which power is transmitted to the centrally disposed shaft 40 45 from which it may be taken by any suitable means.

I claim as my invention:

1. An air motor comprising a frame, upper and lower cables mounted thereon, vane supporting shafts in the same vertical plane 50 with said upper and lower cables, vanes carried by said shafts and having each a series of shutters designed to be automatically opened and closed, sheave wheels for said cables, shafts for said sheave wheels, and means for taking off the power from said shafts.

2. A motor comprising a circularly arranged track, a frame designed to travel on 55 said track, a series of vertically disposed shafts, vanes pivotally mounted on said shafts and having a portion extending on

each side of said shaft, each of said vanes having movable shutters, upper and lower cables to which said vanes are connected, 65 and a rudder connected to said frame and also traveling on said track.

3. An air motor comprising a frame pivotally mounted at its center, pairs of upper and lower horizontally spaced sheave 70 wheels, endless cables engaging said wheels, a series of vanes carried by said cables, each vane extending in working position an equal distance on each side of said cables, and a rudder for regulating the position of said 75 frame.

4. An air motor comprising a frame pivotally mounted at its center, pairs of upper and lower horizontally spaced sheave wheels, endless cables engaging said wheels, 80 a series of independently movable vanes carried by said cables, each vane extending in working position an equal distance on each side of said cables, and a rudder for regulating the position of said frame.

5. The combination with a frame having upper and lower sheave wheels and endless cables engaging said sheave wheels, of a series of vanes, each having a series of pivoted shutters, a shaft arranged midway 90 its length, and means connecting said shafts to said cables in the same vertical plane with the latter.

6. An air motor comprising a frame, upper and lower cables mounted thereon, vertically disposed shafts secured to said cables and in the same vertical plane therewith, a series of vanes pivotally mounted on said shafts and having movable shutters designed to be automatically opened and closed. 95

7. The combination with a frame having upper and lower sheave wheels and endless cables engaging said sheave wheels, of a series of vanes, each having a series of pivoted shutters, one of said shutters having a projecting member, means connecting the vanes to said cables, and means secured to one of said cables with which said projecting member engages. 105

8. The combination with a frame, of upper and lower endless belts, a series of vanes connected to said belts, and having each a series of pivoted shutters, an arm mounted on the frame and designed to be thrown in the path of the vanes, and means for holding the vanes in the position into which they are moved by engagement with such arm. 115

In testimony whereof, I have signed this specification in the presence of two subscribing witnesses:

OLAF L. HOWE.
